UNITED STATES PATENT OFFICE

CARLTON G. TOWNE, OF NEW KENSINGTON, PENNSYLVANIA, ASSIGNOR TO THE ALUMINUM COOKING UTENSIL COMPANY, OF NEW KENSINGTON, PENNSYLVANIA, A CORPORATION OF PENNSYLVANIA

DESIGN FOR A SIPHON BOTTLE

Application filed September 26, 1932. Serial No. 45,073. Term of patent 7 years.

To all whom it may concern:

Be it known that I, CARLTON G. TOWNE, a citizen of the United States, residing at New Kensington, in the county of Westmoreland and State of Pennsylvania, have invented a new, original, and ornamental Design for a Siphon Bottle, of which the following is a specification, reference being had to the accompanying drawing, forming a part thereof.

Fig. 1 is a perspective view of a siphon bottle showing my new design; and Fig. 2 is another perspective view of a part of the same bottle.

I claim:
The ornamental design for a siphon bottle, as shown.

CARLTON G. TOWNE.
